UNITED STATES PATENT OFFICE.

FRANCIS G. DIETZ, OF NEW YORK, N. Y.

DESIGN FOR A GARMENT-SUPPORTER.

SPECIFICATION forming part of Design No. 35,612, dated January 28, 1902.

Application filed December 5, 1901. Serial No. 84,835. Term of patent 14 years.

To all whom it may concern:

Be it known that I, FRANCIS G. DIETZ, a citizen of the United States, residing at New York, in the county of New York and State of New York, have invented and produced a certain new and original Design for Garment-Supporters, of which the following is a specification.

The characteristic feature of my invention is the design for a garment-supporter made the subject of the illustration in the accompanying drawings, in which—

Figure 1 is a perspective view of a garment-supporter made according to my design. Fig. 2 is a top plan view, and Fig. 3 is an edge view of the same.

As shown in the drawings, the garment-supporter made according to my design consists of a base 1 and a hook 2, leading outwardly therefrom. The base 1 is made from a flat strip of material bent at a point intermediate its ends to form the two substantially parallel sides 3 and 4. The outer edge of the side 3 projects beyond the corresponding edge of the side 4 and is provided with a plurality of elongated openings 5. The side 4 is provided on its inner surface with a longitudinally-ex-

tending groove 6, the same being parallel to the outer edge of said side and forming on the outer surface of the same a rib or projection 7. In the groove 6 the inner end of the hook 2 fits and is secured, the rivets 8 extending inwardly beyond the plane of the hook 2 and the plane of the side 4, forming projections 9. The hook 2 extends upwardly above the upper edge of the side 4 and is then bent downwardly in a plane at right angles to the side 4 to form a loop 10. It is then bent downwardly and upwardly in the plane parallel to the side 4 to form the loop 11. It extends up to a point above the plane of the loop 10 and is again bent downwardly in a plane at right angles to the side 4 to form the loop 12.

Having now described my invention, what I claim is—

The design for a garment-supporter, substantially as herein shown and described.

In testimony whereof I have hereunto set my hand in presence of two subscribing witnesses.

FRANCIS G. DIETZ.
